No. 820,631.

PATENTED MAY 15, 1906.

E. ECKART.

SPRAYING DEVICE.

APPLICATION FILED DEO. 30, 1905.

UNITED STATES PATENT OFFICE.

EDMUND ECKART, OF NEW ROCHELLE, NEW YORK, ASSIGNOR TO
GERSTENDORFER BROS., OF NEW YORK, N. Y., A CORPORATION
OF NEW YORK.

SPRAYING DEVICE.

No. 820,631.

Specification of Letters Patent.

Patented May 15, 1906.

Application filed December 30, 1905. Serial No. 293,937.

To all whom it may concern:

Be it known that I, EDMUND ECKART, a citizen of the United States, and a resident of New Rochelle, Westchester county, State of New York, have invented certain new and useful Improvements in Spraying Devices, of which the following is a specification.

My invention relates to devices for atomizing or spraying liquids, and particularly substances of a viscous character, such as paints.

For this purpose my invention embodies improvements in the atomizing-nozzle and also in means for stirring the liquid, so as to keep it in proper condition.

15 A typical embodiment of my invention has been shown in the accompanying drawings, in which—

Figure 1 is a sectional elevation of my improved atomizer. Fig. 2 is a top view. Fig. 3 is a detail section of the atomizing-nozzle, and Fig. 4 is a perspective view of another form of atomizing-nozzle.

The device comprises a suitable receptacle A, which may be of any approved shape and 25 which is provided with a handle B, enabling it to be readily carried from place to place. The receptacle is provided with a top C, which may be held down in any suitable way—as, for instance, by means of nuts D, 30 screwing on bolts E, which are hinged to the receptacle A near the top and are adapted to be swung into slotted lugs C' of the cover C. The cover is also provided with an opening through which the paint or other liquid may 35 be filled into the receptacle, said opening being normally closed by a plug F. The cover carries two brackets C², in which is received adjustably the air-tube G, held in position after adjustment by means of set-screws C³.

40 This air-tube preferably extends along the diameter of the top or cover C and is provided with a nozzle G', which is adjustable lengthwise, as by means of a screw connection. The other end of the tube G is connected with a 45 source of compressed air, and at some suitable point a cock or other regulating device is interposed, so that the jet of air delivered at the nozzle G' may be regulated or discontinued altogether, if desired. In the particular instance shown the end of the tube G opposite to the nozzle G' screws into a pipe H, which extends through the handle B and is provided with a regulating-cock H'. A nut

G² serves to lock the tube G relatively to the pipe H.

55 Adjacent to the nozzle G' is located the paint-nozzle I, which is made of a peculiar shape, as shown in Figs. 1 and 3. On the side next to the nozzle G' the paint-nozzle has an inclined or slightly-curved surface I', 60 which preferably extends to a point almost at the center of the nozzle I. In line with the upper end of this incline I' is provided the opening, such as the slot I², through which the paint or other liquid may issue 65 from the nozzle. As will be clearly seen in Fig. 3, this opening I² is below the upper end of the incline I'. On the other or farther side of the opening I² is another incline I³, 70 which starts at the same level as the opening I² and is continued upward, preferably to a higher level than the upper level of the incline I'. The upper edge I⁴ of the incline I' is preferably horizontal, or about so. The nozzle I is screwed or otherwise fastened to 75 the end of an inclined tube J, which dips into the receptacle A and passes through the cover C. Nuts J' J² may be used for holding the nozzle I in proper relation to the nozzle G'. 80

In order that the paint or other liquid may be conveniently stirred, I provide a perforated plate K, secured to the bail L, which is adapted to slide up and down in the cover C, the upper end L' of the bail forming a handle. 85

The air-jet from the nozzle G' will be deflected upwardly by the incline I' and will induce a current of paint through the outlet I² of the nozzle I. This stream of paint will 90 then be struck directly by the blast of air and forcibly thrown against the incline I³, so that the paint will be subjected to a greater pressure, and therefore will be more minutely subdivided by being forced against such upper incline I³. I therefore secure a very efficient atomizing of the paint. At the same time any heavy particles which may not reach the point where the air-blast strikes the incline I³ will gravitate back toward the 95 outlet I² and will thus get into the path of the induced current. 100

In the form of nozzle shown in Fig. 4 the incline i' is straight instead of curved, as in the form shown in Fig. 3. In other respects 105 both forms are alike.

I claim as my invention—

1. A spraying device comprising a receptacle, an air-nozzle and a liquid-nozzle arranged adjacent to each other, the liquid-nozzle having a connection dipping into said receptacle and having two inclines arranged stepwise and facing the air-nozzle, the higher incline being farther away from the air-nozzle, and the outlet of the liquid-nozzle being between said two inclines.
2. A spraying device comprising a receptacle, a liquid-nozzle and an air-nozzle arranged adjacent to each other, the said liquid-nozzle having an incline facing the air-nozzle and an outlet located beyond the upper end of said incline, but at a lower level.
3. A spraying device comprising a receptacle, a liquid-nozzle and an air-nozzle arranged adjacent to each other and one adjustable relatively to the other, the said liquid-nozzle having two inclines facing the air-nozzle and an outlet located between said two inclines.
4. A spraying device comprising a receptacle, a liquid-nozzle and an air-nozzle arranged adjacent to each other and one ad-

justable relatively to the other, the said liquid-nozzle having an incline facing the air-nozzle and an outlet located beyond the upper end of said incline, but at a lower level. 30

5. The combination of the receptacle, the liquid-nozzle having a tube dipping into said receptacle, the stirrer movable adjacent to the inlet end of said tube, and the air-nozzle adjustable toward and from the liquid-nozzle, the said liquid-nozzle having inclines arranged stepwise and facing the air-nozzle, and a depressed outlet arranged between said inclines. 35

6. A spraying device comprising a receptacle, a liquid-nozzle and an air-nozzle arranged adjacent to each other, the said liquid-nozzle being provided with two inclines and an outlet located between said inclines. 40

In testimony whereof I have hereunto signed my name in the presence of two subscribing witnesses.

EDMUND ECKART.
